UNITED STATES PATENT OFFICE.

JOHN M. WEISS, OF NEW YORK, N. Y., AND GEORGE C. BAILEY, OF WOODCLIFF-ON-HUDSON, AND RALPH S. POTTER, OF GRANTWOOD, NEW JERSEY, ASSIGNEES TO THE BARRETT COMPANY, A CORPORATION OF NEW JERSEY.

PRODUCTION OF CHLOROBENZOYL BENZOIC ACID.

1,355,100.

Specification of Letters Patent.

Patented Oct. 5, 1920.

No Drawing.

Application filed December 12, 1919. Serial No. 344,460.

To all whom it may concern:

Be it known that we, JOHN M. WEISS, GEORGE C. BAILEY, and RALPH S. POTTER, citizens of the United States, residing at (1) New York city, (2) Woodcliff-on-Hudson, and (3) Grantwood, in the counties of (1) New York, (2) Hudson, and (3) Bergen, and States of (1) New York, (2) and (3) New Jersey, have invented certain new and useful Improvements in Production of Chlorobenzoyl Benzoic Acid, of which the following is a specification.

This invention relates to the production of p-chlorobenzoyl-o-benzoic acid from phthalic acid anhydrid and chlorobenzol by means of aluminum chlorid. The objects of the invention are to increase the yield, to increase the rapidity of production and to economize in the use of materials.

The invention relates more particularly to improvements in the production of beta-chloroanthra-quinone from phthalic acid anhydrid and chlorobenzol which has been described in German Patent No. 75,288. In this patent, it is directed that aluminum chlorid be introduced into the hot solution of 100 parts of phthalic anhydrid in 1000 parts of chlorobenzol in small portions until the evolution of hydrochloric acid gas ceases. No information as to the preferable temperature is given in this patent. We have found that if the directions of the patent are followed, there will be some production of the chlorobenzoyl benzoic acid, but that the temperature at which the introduction of the aluminum chlorid is carried out is very important. We have also found that aluminum chlorid may be introduced into a hot mixture of phthalic anhydrid and chlorobenzol in a greatly excessive amount with but little diminution in the evolution of hydrochloric acid gas with each successive portion of aluminum chlorid added. We have found that aluminum chlorid when added to hot chlorobenzol alone gives off an amount of hydrochloric acid gas closely approximating one molecule of this gas for each molecule of aluminum chlorid used. If the directions of the German patent are followed, hydrochloric acid gas will be given off until about a molecule of aluminum chlorid is added per molecule

of chlorobenzol present. We have found that good yields of the chlorobenzoyl benzoic acid may be obtained with a much less quantity of aluminum chlorid. It has also been found that increased yields may be obtained by an introduction of a mixture of phthalic anhydrid and aluminum chlorid into the hot chlorobenzol over those obtained by the introduction of the aluminum chlorid into the hot mixture of the chlorobenzol and the phthalic anhydrid as directed in the patent. In addition, we have found the most suitable temperatures at which the reaction should be carried out in order to obtain the highest yields. We have found these temperatures to be from 110° C. to just below the boiling point of the mixture. This boiling point varies, according to the amount of solids introduced, from 130° to 134° C. We have found a convenient range to be 118° to 123° C. Noticeably lower yields are obtained if these limits are exceeded, especially if the mixture be boiled.

We have also found that the quality of the aluminum chlorid is very important. For example, when the ordinary, pure sublimed aluminum chlorid of commerce is used, yields of the chlorobenzoyl benzoic acid approximating 50% of theory based on one molecule of phthalic anhydrid and 2 molecules of aluminum chlorid ($AlCl_3$) charged are obtained. When the fine particles, small enough to pass through a 20-mesh screen, are sifted out and the coarser pieces of the chlorid are used, yields of twenty to twenty-five per cent. higher are obtained. Use of the fine particles, the siftings, gives yields 20 to 30% lower than where the coarse and the fine are used together. However, if the coarse material is ground to sufficient fineness to pass through a 20-mesh screen or even finer, it will still give yields as large as the original coarse aluminum chlorid. It seems probable, therefore, that the siftings from the commercial product are less pure than the large particles, and in order for the same to be converted into aluminum chlorid suitable for the purposes of this invention, the siftings must be re-sublimed. Although not desiring to commit ourselves

to any definite theory for the explanation of this phenomenon, we suggest that poor yields may be due to hydrolysis of the aluminum chlorid.

5 Phthalic acid anhydrid is usually obtained in the form of large needles. We have found that the acid in this form is less suitable for this process than it is when finely ground. We accordingly comminute 10 the phthalic acid anhydrid preferably to such fineness that it will pass through an 80-mesh screen and thereby obtain higher yields of the chlorobenzoyl benzoic acid than can be obtained with the ordinary large crystals.

15 We have made another improvement over the German patent in the step of precipitating the chlorobenzoyl benzoic acid. In the German patent, it is directed that after the reaction mass has cooled that it be poured 20 into water and then decomposed by boiling with sodium carbonate. The alumina is then filtered off and the chlorobenzoyl benzoic acid precipitated from the filtrate by means of mineral acids. By this present invention, we have greatly cheapened and 25 shortened this step of the process. We accomplish this result by adding water to the reaction mass after it has cooled, and then adding approximately one molecule of sulfuric acid per molecule of phthalic anhydrid originally charged. The excess chlorobenzol may then be removed by steam distillation. The chlorobenzoyl benzoic acid is obtained directly as a precipitate upon adding 30 the sulfuric acid as above mentioned and may be filtered and washed by the usual means. Aluminum sulfate may be obtained by evaporating the filtrate from the chlorobenzoyl benzoic acid after the addition of 35 sufficient sulfuric acid to convert all the aluminum to the sulfate. This procedure not only saves the cost of the sodium carbonate, but also saves the troublesome filtration 40 of the alumina.

45 The chlorobenzoyl benzoic acid may be used for any of the purposes for which it is adapted in the arts, but is especially valuable as an intermediate product for the production of alizarin. In producing alizarin, 50 the acid is condensed to chloro-antra-quinone, for example, by treating with concentrated sulfuric acid, and is then converted into alizarin in any convenient way, as by 55 treating it with caustic alkali in the presence of an oxidizing agent.

Having described the general procedure, a specific example is given below. It is to be understood that the proportions of materials and the temperatures may be varied somewhat from those given in the example without departing from the spirit and scope of the invention. The parts are by weight.

60 100 parts of finely ground phthalic anhydrid are mixed with 180 parts of coarse 65 freshly sublimed aluminum chlorid. This

mixture is gradually added with agitation to 1000 parts of chlorobenzol held at a temperature of 120° C. The hydrochloric acid gas given off may be recovered. After the phthalic acid anhydrid and aluminum chlorid mixture has all been introduced, the temperature is kept at about 120° C. for a short time. After cooling, water or ice is added to the mixture and then 80 to 90 parts of 70 60% H₂SO₄ added. The excess chlorobenzol is then removed by steam distillation. The crude chlorobenzoyl benzoic acid is filtered from the cooled mass. The addition of 75 the proper amount of sulfuric acid and the concentration of the filtrate will give approximately 280 parts of aluminum sulfate. The crude chlorobenzoyl benzoic acid is then 80 dried and washed.

If any phthalic acid anhydrid is present from the first reaction, as phthalic acid, it 85 may be recovered either by filtering the hot reaction mixture after the chlorobenzol was removed by steam distillation, in which case the phthalic acid will separate from the cooled filtrate and the chlorobenzoyl benzoic acid will remain as the undissolved residue, or the mixture from the steam distillation may be cooled and then filtered, in which case the phthalic acid may be extracted from the crude chlorobenzoyl benzoic acid by extraction with hot water. 90 95

Claims:

1. In the process of producing chlorobenzoyl benzoic acid, the step which comprises 100 treating phthalic acid anhydrid with chlorobenzol in the presence of commercial aluminum chlorid from which substantially all of the particles small enough to pass through a 20-mesh screen have been removed.

2. In the process of producing chlorobenzoyl benzoic acid, the step which comprises 105 introducing a mixture of phthalic acid anhydrid and aluminum chlorid into chlorobenzol maintained at a temperature above 110° C.

3. In the process of producing chlorobenzoyl benzoic acid, the steps which comprise 110 introducing a mixture of phthalic acid anhydrid and aluminum chlorid into chlorobenzol, while maintaining the temperature between 110° C and the boiling point of the solution while the reaction is taking place.

4. In the process of producing chlorobenzoyl benzoic acid, the steps which comprise 115 introducing a mixture of phthalic acid anhydrid and aluminum chlorid into chlorobenzol, while maintaining the temperature between 118° C and 123° C.

5. In the process of producing chlorobenzoyl benzoic acid, the steps which comprise 120 introducing a mixture of phthalic acid anhydrid and aluminum chlorid into chlorobenzol and maintaining the temperature at about 120° C. for a short time, distilling off the excess chlorobenzol, filtering, recovering 125 130

unreacted phthalic anhydrid, and drying the chlorobenzoyl benzoic acid.

6. In the process of producing chlorobenzoyl benzoic acid, the steps which comprise introducing a mixture of phthalic acid anhydrid and aluminum chlorid into chlorobenzol maintained at a temperature between 110° C. and the boiling point of said mixture, in substantially the proportions of 100

parts of phthalic anhydrid and 180 parts of aluminum chlorid to 1000 parts of chlorobenzol.

In testimony whereof we affix our signatures.

JOHN M. WEISS,
GEORGE C. BAILEY,
RALPH S. POTTER.
